UNITED STATES PATENT OFFICE.

WILLIAM V. CRUESS, OF BERKELEY, CALIFORNIA, DEDICATED, BY MESNE ASSIGNMENTS, TO THE GOVERNMENT OF THE UNITED STATES AND TO THE PEOPLE OF THE UNITED STATES.

PROCESS FOR PICKLING OLIVES.

1,257,584.

Specification of Letters Patent. Patented Feb. 26, 1918.

No Drawing.

Application filed November 5, 1917. Serial No. 200,427.

(DEDICATED TO THE PUBLIC.)

To all whom it may concern:

Be it known that I, WILLIAM V. CRUESS, a citizen of the United States, residing in the city of Berkeley, county of Alameda, 5 State of California, (whose post-office address is Berkeley, California,) have invented a certain new and useful Improvement in Processes for Pickling Olives.

This application is made under the act of 10 March 3, 1883, chapter 143 (22 Stat., 625), and the invention herein described and claimed may be used by the Government of the United States or any of its officers or employees in the prosecution of work for 15 the Government, or any person in the United States, without payment to me of any royalty thereon.

My invention relates to processes for pickling olives. Heretofore, olives have been 20 treated in the process of pickling with one or more dilute solutions of potash or other lye, the purpose of such treatment being to destroy and facilitate the extraction of the bitter elements from the olives. After the 25 treatment the lye and bitter elements are extracted by repeated soakings of the olives in water. The olives are then placed in one or more salt brines and finally canned. As a result of this treatment, the olives be- 30 come bleached more or less, due to the application of the lye, and the bleaching operates to make the olives uneven and too light in color. To counteract this effect upon the olives by the treatment described, the olives 35 are exposed one or more times to the air, either during or subsequent to immersion in the lye solution. Exposing the olives in this way to the action of the air tends to darken and equalize the color defects of the fruit. 40 The bleaching of the olives is an objectionable feature of the known process for canning the fruit. Aside from this, such process possesses the following disadvantages:

1. The time consumed from the beginning of the application of the lye treatment to the olives to the completion of canning is from three to six weeks, or longer.
2. The pickling vats and other parts of

the equipment of the pickling factory can be used only twice, as a general rule, in one 50 season. This limits the capacity of the factory.

3. A great deal of hand labor is necessary in turning and stirring the olives during exposure to air to darken them. This labor 55 is costly.

4. This stirring results in a great deal of bruising of the olives.

5. Because of the great length of time necessary by the usual method, the olives are 60 exposed to decomposition by bacteria. A very appreciable amount of olives is lost in this way.

6. The color of olives colored by exposure to air is not uniform because the points at 65 which the olives are in contact with each other are not exposed to the air as much as the remaining surface of the olives and light spots result at these points of contact. The flesh of the olives colored by exposure is 70 darkened; a very objectionable feature.

7. Small vats must be used. If large ones are employed the weight of the olives during exposure to the air will crush and bruise the olives in the bottom of the vats. 75

8. Some olives require an excessively long exposure to the air. This long exposure results in injury to the texture and quality of the fruit.

The object of my invention is to provide 80 a simple process easy of application, which will obviate the disadvantages of present processes, as hereinbefore particularized. To accomplish this end, I treat the olives with one or more solutions of potash or other 85 lye substance; this lye solution being heated before addition to the olives or during the treatment of the olives with the lye solution, or the lye solution is added as in present methods without heating. 90

After the lye treatment, the olives are subjected to treatment with running water or liquid which is made or allowed to flow over and between the olives, with or without aeration of the water or liquid. Or the olives are 95 subjected to treatment with water which is

not caused to circulate or flow. The water is heated before or while it flows over and between the olives. Aeration of the water or liquid during this treatment is not an essential part of the process and is not necessary to its successful application.

The novel features of my process is the heating of the water and other liquids used in the pickling process or the heating of the 10 olives themselves.

Circulation of the water or other liquid used in treating the olives may be accomplished by drawing the liquid from the bottom of the picking tank or container and 15 pumping it back over and between olives; or water from a tank or reservoir or other source of supply may be allowed to run over and between the olives and out of the vat to a sewer or allowed to escape in any other way, 20 being used for the olive treating only once. It may also be allowed to flow from the pickling vats into a sump or receiver of any convenient kind and then be pumped to a tank or reservoir elevated above the pickling 25 or vats. It may then be allowed to flow by gravity back through the pickling tanks or vats.

The water or the liquid may be heated in the supply tank or reservoir, from which it 30 flows to the pickling vats or tanks, or it may be heated in the pipes used to deliver the liquid to the picking tanks or vats; or it may be passed through and heated in any suitable form of heating apparatus placed between the supply tank or reservoir and the 35 picking tanks or vats; or the water or other liquid may be heated in the pickling vats or tanks themselves.

The circulation or flowing of the water, 40 or other liquid over and between the olives may be omitted. The water or other liquid may be simply allowed to stand without circulation or flowing on the olives in the picking vats or tanks. It is kept heated in the 45 vats or tanks or is heated before being added to the pickling vats or tanks. The water or other liquid may be changed often to facilitate removal of the lye from the olives and darkening of the color.

50 My process may be applied in the method of pickling olives where they are exposed to the air to darken them. In this case, the lye, the water and brine are heated or only one or two of these liquids may be heated as de- 55 sired.

The advantages obtained in practising my process may be briefly summarized as follows:—

1. It avoids exposure of the olives to the 60 air to darken them.
2. It decreases the amount of labor necessary in handling the fruit.
3. It diminishes the length of time necessary for curing or pickling the olives.

Where heated flowing water is used as described in my process for pickling olives after the lye treatment, it is possible to complete the pickling operation in three to six days as compared with three to six weeks in the present methods. 70

4. The output of the factory can therefore be greatly increased because the pickling vats can be used several times during the season.

5. The color of the olives cured or pickled 75 by my process is uniform and is localized near the surface.

6. There is no danger of loss of olives by bacterial decomposition, because the time necessary for my process is so short that this 80 decomposition can not take place.

7. It enables large pickling vats to be used in the pickling or curing of olives.

8. It results in olives of uniformly good quality and color and eliminates to a very 85 large degree the element of chance now so prominent in present methods of pickling olives.

Having thus described my invention, I 90 claim:

1. The process for pickling or curing olives, consisting in heating the lye solution, the water, and other liquids used in treating the olives subsequent to the lye treatment.

2. The process for pickling or curing 95 olives, consisting in heating the water and other liquids used in treating the olives, and causing the water and other liquids to flow over and between the olives.

3. The process for pickling or curing 100 olives consisting in heating and aerating the water and other liquids used in treating the olives and passing the liquids over and between the olives.

4. The process of pickling olives which 105 consists in heating the liquids in which the olives are treated and in aerating said liquids with compressed air.

5. The process for pickling or curing 110 olives which consists in subjecting the olives to a lye bath, and subsequently subjecting the olives in a tank to a heated liquid carrying minute particles of air in suspension, continuously withdrawing the liquid from the bottom of the tank, continuously adding 115 air to said withdrawn heated liquid and intimately mixing said air and heated liquid and causing the mixture to flow back into the tank continuously.

6. The process for pickling or curing 120 olives in which the olives are heated during exposure to air after lye treatment.

7. The process for pickling or curing olives in which the water used in treating the olives is heated and withdrawn and replaced by fresh water frequently but not continuously. 125

8. The process for pickling or curing

olives in which the water used in treating the olives is heated, withdrawn, and replaced with other heated aerated water.

9. The process of pickling or curing olives in which the water used in treating the olives is heated and withdrawn frequently, aerated, and returned to the olives.

10. The process of pickling or curing olives which consists in subjecting the olives

during the pickling or curing process to heated and moving liquids carrying oxygen in solution.

In witness whereof, I affix my signature in the presence of two subscribing witnesses.

WILLIAM V. CRUESS.
